(57) **CLAIM**

The design for a computer stand, as shown and described.

DESCRIPTION

FIG. 1 is a perspective view of the closed computer stand showing the top, front side and right side of the computer stand. The left side is a mirror image of the right side.

FIG. 2 is a right side elevation of the opened computer stand. The left side is a mirror image of the right side.

FIG. 3 is a front elevation of the opened computer stand.

FIG. 4 is a top view of the opened computer stand.

FIG. 5 is a right side elevation of the closed computer stand. The left side is a mirror image of the right side.

FIG. 6 is a top view of the closed computer stand; and,

FIG. 7 is a perspective view of the opened computer stand showing the top right side and front of the opened computer stand.

The bottom is flat and devoid of surface ornamentation.
